UNITED STATES PATENT OFFICE

GIDEON GARFIELD HASSLER, OF STOWE TOWNSHIP, ALLEGHENY COUNTY,
PENNSYLVANIA

DIESTOCK

Original application filed June 4, 1928, Serial No. 282,520. Divided and this application filed June 11, 1931. Serial No. 543,587.

This application is a division of my pending patent application Serial Number 282,520 filed in the United States Patent Office on June 4, 1928, and upon which Letters Patent No. 1,813,668 were issued on July 7, 1931.

5 More particularly my present invention relates to means for centering the die-stock and dies relative to the work.

In my improved portable die-stock the two stock-parts are in hinged relation to each 10 other and centering blocks are slidably mounted in the stock-parts in slideways disposed radially of the work, and said blocks are arranged to impinge on the work and thus center the threading or cutting dies relative 15 to the work.

Means are provided for causing and controlling the unitary movement of said centering blocks.

20 Thus in the preferred embodiment of my invention the centering blocks are moved by means of levers rotatably mounted on the stock-parts and which are provided with eccentric slots which are engaged by projections of the blocks, the movement of the levers serving to advance or retract the centering blocks relative to the work.

25 The arrangement is such that when the die-stock is closed the plates are caused to move in unison so that a unitary movement be imparted to the blocks.

Other novel features of construction and arrangement of parts will appear from the following description.

30 In the accompanying drawing, wherein I have illustrated a practical embodiment of the principles of my invention, Fig. 1 is a rear face view of the die-stock shown closed.

Fig. 2 is a like view with the centering levers removed to disclose the centering blocks.

Fig. 3 is an inner face view of one of the centering levers.

Fig. 4 is an edge view of the same.

45 Fig. 5 is a broken section taken along the line 5—5 in Fig. 1.

Referring to the drawing, the portable die-stock illustrated therein is of the general construction which is the subject matter of my 50 pending patent application and therefore the

portions thereof which are not per se the subject matter of the present application are not herein described in full but reference is made to said pending patent application for a detailed description thereof.

55 The portable die-stock is comprised of the two complementary stock-parts 1 and 1a which are provided at one side with interlacing hinge leaves 2 pivotally connected together by the pintle 3. Each of the stock-parts is provided with a handle 4.

The stock-parts are locked in their closed relation by means of the lever 16 and latch 18, as more fully appears in my pending patent application.

60 The rear face of the stock-parts 1 and 1a are provided with pairs of converging slideways 22, disposed radially of the axis of the stock when closed, in which slideways are slidably mounted the centering blocks 23 which are intended to engage the work and 65 properly center the die-stock relative thereto.

70 The blocks 23 are provided with pins 24 which engage eccentrically disposed slots 25 of like cam-value in the adjustment levers 26 which are provided with arcuate lips 27 on their inner faces which slidably engage arcuate undercut shoulders 28 on the stock-parts.

75 The shoulders 28 are struck on an equal radius described from the axis of the closed stock as a center.

80 The levers 26 are held in place by means of headed bolts 29 screwed into the stock-parts and engaging slots 30 in the levers concentric with their lips 27.

85 The levers 26 are provided with handles 31 and the inner ends of the levers are squared so as to mate together when the stock is closed and thus to move together about a common center so as to advance or retract the centering bars in unison.

90 By means of the centering blocks the stock may be quickly and accurately centered relative to the work. The independence of the control of the centering blocks relative to the threading dies is of particular advantage where the shank of the work in the rear of the portion which is to be threaded is of less or greater diameter than that of the portion to be threaded.

When the stock is closed, the interengagement of the control levers automatically equalizes the positions of the centering blocks, so that when the levers are moved in unison the consequent movement of the centering blocks is the same and thus their positions relative to the common center, thus absolutely insuring an accurate centering of the threading dies relative to the work. The levers may be held fixed in place by tightening the bolts 29 and thus the adjustment of the centering blocks will not be disturbed by the opening and closing of the die-stock.

What I desire to claim is:—

1. In a portable die-stock, the combination with the stock-parts in hinged relation to each other and arranged to carry the dies, of work-centering members slidably mounted on said stock-parts for movement toward and away from the axis of the die-stock when closed, a lever mounted on each of said stock-parts and provided with surfaces disposed eccentrically to the axis of the movements of the levers which engage said members to adjust the position of the same, and means whereby said levers coact to move said members in unison when the die-stock is closed.

2. In a portable die-stock, the combination with the stock-parts in hinged relation to each other and arranged to carry the dies, of work-centering members slidably mounted on said stock-parts for movement toward and away from the axis of the die-stock when closed, a lever mounted on each of said stock-parts and provided with surfaces disposed eccentrically to the axis of the movements of the levers which engage said members to adjust the position of the same, means whereby said levers coact to move said members in unison when the die-stock is closed, and means for fixing said centering members against movement.

3. In a portable die-stock, the combination with the stock-parts in hinged relation to each other, said parts being provided with slideways which are radially disposed relative to the axis of the closed stock, work-centering members movable in said slideways, a lever on each of said stock-parts arranged for rotary movement, and eccentrically disposed slots in said levers engaged by portions of said members whereby when said levers are swung said members are adjusted relative to the axis of the stock.

4. In a portable die-stock, the combination with the stock-parts in hinged relation to each other, said parts being provided with slideways which are radially disposed relative to the axis of the closed stock, work-centering members movable in said slideways, a lever on each of said stock-parts arranged for rotary movement, eccentrically disposed slots in said levers engaged by portions of said members whereby when said levers are swung said members are adjusted

relative to the axis of the stock, and means for fixing said centering members against movement relative to the stock-parts.

5. In a portable die-stock, the combination with the stock-parts in hinged relation to each other, said parts being provided with slideways which are radially disposed relative to the axis of the closed stock, work-centering members movable in said slideways, a lever on each of said stock-parts arranged for rotary movement, eccentrically disposed slots in said levers engaged by portions of said members whereby when said levers are swung said members are adjusted relative to the axis of the stock, and means whereby when the stock is closed the members move in unison whereby a like adjustment of all the members is produced.

6. In a portable die-stock, the combination with the stock-parts in hinged relation to each other, said parts being provided with slideways which are radially disposed relative to the axis of the closed stock, work-centering members movable in said slideways, a lever on each of said stock-parts arranged for rotary movement, eccentrically disposed slots in said levers engaged by portions of said members whereby when said levers are swung said members are adjusted relative to the axis of the stock, and means whereby when the stock is closed said levers interengage so as to move in unison whereby a like adjustment of all the centering members is produced.

7. In a portable die-stock, the combination with the stock-parts in hinged relation to each other, said parts being provided with slideways which are radially disposed relative to the axis of the closed stock, work-centering members movable in said slideways, a lever on each of said stock-parts arranged for rotary movement, eccentrically disposed slots in said levers engaged by portions of said members whereby when said levers are swung said members are adjusted relative to the axis of the stock, means whereby when the stock is closed said levers interengage so as to move in unison whereby a like adajustment of all the centering members is produced, and means for fixing said levers against movement relative to the stock-parts.

Signed at McKees Rocks this 9th day of June, 1931.

GIDEON GARFIELD HASSLER.
